UNITED STATES PATENT OFFICE.

JACOB B. STRUBLE, OF NEW YORK, N. Y., ASSIGNOR TO THE UNION SWITCH AND SIGNAL COMPANY, OF SWISSVALE, PENNSYLVANIA, A CORPORATION OF PENNSYLVANIA.

RAILWAY SIGNALING.

1,092,459.

Specification of Letters Patent.

Patented Apr. 7, 1914.

Continuation of applications Serial No. 82,523, filed November 16, 1901, and Serial No. 97,861, filed March 12, 1902. This application filed March 4, 1904. Serial No. 196,474.

To all whom it may concern:

Be it known that I, JACOB B. STRUBLE, a citizen of the United States, residing in the borough of Manhattan, city, county, and State of New York, have invented certain new and useful Improvements in Railway Signaling, of which the following is a specification.

This application is a continuation of my application filed November 16th, 1901, Ser. No. 82,523, which matured into Pat. No. 819,322 granted May 1, 1906, and of my application filed March 12, 1902, Ser. No. 97,861, which matured into Patent No. 819,323 granted May 1, 1906. This application was pending contemporaneously with the said earlier applications.

My invention relates to railway signaling, and especially to a signaling system for electric railways wherein one or both of the track rails are used as a return conductor for the propulsion current. It is customary in electric railways to employ direct current for operating the car or train motors and to employ one or both of the rails as a return conductor for the propulsion current. In the present invention I employ alternating current in the track circuits of the signaling system, to which translating mechanisms included in the track circuits, are responsive in their control of the railway signals.

I will describe a railway signaling system embodying my invention and then point out the novel features thereof in claims.

In the accompanying drawings, Figure 1 is a diagrammatic view illustrating a portion of an electric railway having a signaling system embodying my invention applied thereto. Fig. 2 is a similar view and illustrating a modification of my invention. Fig. 3 is a view similar to Fig. 1 and illustrating another modification of my invention. Fig. 4 is a detail view of an impedance in the form of a reactance or choke coil, which may be employed in my invention.

Similar letters of reference designate corresponding parts in all of the figures.

Referring now to the drawings and particularly to Fig. 1, in the practice of my invention one of the lines of rails of the railway is divided into a series of sections 1, 2, 3, etc., by means of insulation at suitable

points, while the other line of rails 4 is 55 preferably made electrically continuous. The sections 1, 2, 3, etc., may be of any desired length and in the art each section and the opposite portion of the continuous rail 4 is generally termed a "block section." 60

6^a designates a direct current generator and 6^b a feed conductor extending therefrom and along the line of railway and from which current is obtained for the motors of the cars traveling along the railway. 65 The return for the direct or propulsion current is through one or both track rails, they being bonded or joined together for this purpose in the manner hereinafter described.

14 designates a railway signal, at least 70 one being provided at the beginning of each block section. The railway signals 14 may be of any desired construction and they each preferably comprise a semaphore and mechanism or means for moving the semaphore 75 from one position of indication to another.

5 designates an alternating current generator. One pole of the alternating current generator is here shown as being connected with the line of rails 4, while the other pole 80 of the generator 5 is connected with a conductor 5^a extending along the line of railway, and which at some suitable point, for example, at the end of the railway, is electrically joined to the lines of rail 4. 85

6 designates transformers, at least one transformer being provided for each block section. As shown in the drawings, the primary windings of the transformers are in series with the conductor 5^a, and their secondary windings are electrically connected to the opposite lines of rails comprised in each block section. It will be understood that other arrangements of the conductors extending from the alternating current generator 5 may be provided as well as other arrangements of the primary windings of the transformer. The employment of transformers permits of a high tension current extending through the generator 5 and 95 the use of low tension currents in the track circuits. To prevent an excessive amount of alternating current flowing in a track circuit when a train is in the block section, a resistance 7 is arranged in the track circuit, 100 (as shown, in one of the connections in the secondary winding with track rail) or each transformer 6 may be built with such re-

sistance as it is well known in the art. The track circuit of each block section comprises all or portions of the track rails of the block section, a transformer or the secondary winding thereof, and a translating mechanism or device.

8 designates translating mechanisms or devices, one being provided for each track circuit. Each translating mechanism is in the form of a relay, the coil or coils 18 of which are included in the track circuit. The armature 19 of the relay is pivotally mounted in operative relation to the poles of the magnet core energized by the coil or coils 18. The form of translating device and its operation is more particularly set forth in my United States Patent No. 819,323 issued May 1, 1906. This form of translating mechanism as set forth in the patent hereinbefore referred to is responsive to the alternating current in the track circuit for one of its operations to control a local circuit 13, which circuit includes a source of electrical energy and a controlling device of the mechanism of the signal 14, and when the alternating current is shunted from the coil or coils 18, for example, by the wheels and axles of the train on the track rails of the track circuit in which the translating mechanism is included, it will respond to again control the circuit 13. In other words, when alternating current is flowing through the coil or coils 18, the armature 19 will move to close the circuit 13 and when alternating current is shunted from the coil or coils 18, the armature 19 will move to open the circuit 13. In both conditions of the circuit the mechanism of the railway signal will be affected to have the semaphore thereof give different indications. Any other form of translating mechanism may be employed.

17 designates impedances in the form of reactance, or choke coils, see Fig. 4, which may be constructed in accordance with the rules well known in the art. The coils may be connected across the wires or conductors connecting the translating mechanisms with the track rails and across the wires connecting the secondaries of the transformers 6 or with the track rails. These coils will permit of direct current flowing through them but will prevent alternating current flowing through them, the effect, therefore, being to confine alternating current to the several track circuits and to permit direct current to pass from the track rails of one track circuit to the track rails of another track circuit. In other words, the direct or propulsion current for the car motors may be flowing through both track rails as a return without in any way affecting the apparatus connected therewith.

Instead of having the coils 17 connected across the track rails, they may be arranged

to connect adjacent ends of the insulated sections as shown in Fig. 2. In Fig. 3 a reactance coil is placed across the conductors connecting the translating mechanisms with the track rails. Otherwise the figure is the same as Fig. 2. In either arrangement the propulsion current will pass through the track rails to the generator. Each coil is made with low ohmic resistance so as to form an easy path from rail to rail, while the flow of alternating current is prevented by the reactive effect of self-induction so that the reactance coil has a choking effect on the alternating current but not on the direct current. The coils and the other instruments connected with the track circuits will be constructed in the proper proportions and with the proper resistances to carry out my invention.

What I claim as my invention is:

1. In a signaling system for railways having one of its lines electrically continuous and its other line of rails divided into insulated sections, the combination of a series of track circuits, an alternating current generator, a series of transformers, one being provided for each track circuit, a translating mechanism for each track circuit operable by the alternating current of the track circuit and constructed to induce a current in another circuit and thereby control a railway signal, a series of railway signals, one being provided for each track circuit and reactance coils for connecting both ends of the insulated rail sections with the continuous rail.

2. In a signaling system for railways having one of the lines of rails electrically continuous and the other line of rails divided into insulated sections, a track circuit which comprises a portion of the electrically continuous rail and an insulated section of the other track rail, reactance coils connecting the ends of the insulated rail sections with the continuous rail, a source of alternating current supply and a translating device.

3. In a system of electrical distribution and signaling for railways, the combination of two sources of electric energy transmitting currents different in character, an outgoing conductor from one of said sources which forms the feeding conductor, a return conductor formed of the two rails of the railway, said conductor divided into blocks and having reactance devices interposed between the rail sections of the blocks and the source of energy, a transformer for each block having its secondary across the rails of a block and signaling devices under the control of the current transmitted through the transformers connected to each block.

4. In combination with a railway the rails of which are employed as a return for the propulsion current employed for the motors of the cars traveling along the rail.

- way and one of said rails being electrically continuous and the other of said rails being divided into insulated sections, a feed conductor for the propulsion current extending 5 along the line of railway, and a signaling system, said system comprising a series of track circuits, an alternating current generator, means for supplying alternating current to said track circuits, a translating mechanism for each track circuit, and reactance coils connected with said track rails whereby the propulsion current will flow through the rails as a return and will be shunted from the translating mechanism. 10
5. In an electric railway signaling system, employing a closed signal controlling track circuit, a plurality of block sections, one rail being divided into insulated sections corresponding to the block sections, a signal 15 for each block section operable by an alternating current, a source of alternating current for said signals, a source of direct current for propelling the railway cars, and means for permitting the direct current to 20 pass from one insulated rail section to another and for preventing alternating current from passing from one insulated rail section to another. 25
6. A system of electrical distribution and 30 signaling for railways, comprising two sources of electrical energy delivering currents differing in character, one source connected to a feeder conductor and to each of the track rails as return conductors to the 35 source of energy and adapted to energize the car motors on said rails, and the other source of energy connected across segregated blocks of the track rails and adapted to energize signaling mechanisms located in said blocks. 40
7. In an electric railway signaling system, the combination of a closed track circuit, a source of alternating current for said track circuit, a plurality of block sections, one of the rails being divided into sections corresponding to the block sections, and a signal 45 for each section operable by said current, and means for permitting the use of both rails as a return for the direct car propulsion current. 50
8. In an electric railway signaling system, the combination of a closed track circuit, a source of alternating signaling current for said track circuit, a plurality of block sections, one of the rails being divided into 55 sections corresponding to the block sections, a signal for each section operable by said current, and a path of low ohmic resistance from one rail section to another for direct current and high impedance to the alternating signaling current. 60
9. In an electric railway signaling system, the combination of a closed track circuit, a source of alternating signaling current for said track circuit, a plurality of block sections, one of the rails being divided into 65 sections corresponding to the block sections, a signal for each section operable by said current, and a path of high impedance to the alternating signaling current from one rail section to an adjacent rail section. 70
10. In an electric railway signaling system, the combination of a closed track circuit, a source of alternating current for said track circuit, a plurality of block sections, one of the rails being divided into sections 75 corresponding to the block sections, a signal for each section operable by said current, and a path of low resistance to direct current and of high impedance to the alternating current, connecting one rail section to another. 80
11. In an electric railway signaling system, the combination of a closed track circuit, a source of alternating current for said track circuit, a plurality of block sections, one of the rails being divided into sections 85 corresponding to the block sections, a signal for each section operable by said current, and an inductive impedance winding in a connection between adjacent rail sections. 90
12. A system of electrical distribution and 95 signaling for railways, comprising two sources of electrical energy delivering currents differing in character, conductors of which each traffic rail forms a part, are divided into blocks and serve as separate return paths to the sources of energy, a motor car driven from one of said sources of energy, current transforming devices having their primaries energized from the other 100 source of energy, and their secondaries connected across the rails of the separate blocks, and signaling devices in each block normally actuated by the current across the rails of the block. 105
13. A system of electrical distribution and 110 signaling for railways, comprising two sources of electrical energy delivering currents differing in character, conductors of which each traffic rail forms a part, are divided into blocks and serve as separate return paths to one of the sources of energy, means interposed between the other of said sources of energy and the track rails of a block for modifying the current from said 115 source of energy delivered across the rails of said block, and means in each block actuated from said last named source of energy and adapted to indicate the condition of the block. 120
14. A system of electrical distribution and 125 signaling for railways, comprising two sources of electrical energy delivering currents differing in character, conductors of which both rails form a part and said rails divided into blocks through which the currents from said sources of energy are transmitted, means interposed between one of the sources of energy and the track rails for modifying the current from said source of 130

- energy delivered to such track rails, a signaling device in each block, a source of energy therefor, and means interposed between the rails of each block and each signaling device and normally adapted to actuate mechanism to close a circuit through a source of energy connected to a signaling device and to be rendered inoperative when a car enters a block.
- 10 15. A system of electrical distribution and signaling for railways, comprising two sources of electrical energy delivering currents differing in character, feeder conductors leading therefrom, track rails arranged as a series of blocks and connected to separately serve as return paths for the power circuit, one source of energy connected to the power circuit and adapted to energize the car motors; and the other source of energy connected across the rails of each block and adapted to energize a signaling mechanism situated in each block.
- 15 20. In a system of electrical distribution and signaling for railways, the combination of two sources of electric energy transmitting currents different in character, an outgoing conductor from one of said sources which forms the feeding conductor, a return conductor formed of the two rails of the system, said conductor divided into blocks, and having reactance devices interposed between the ends of the rail sections of the blocks and the source of energy, an outgoing and return conductor connected to the other source of energy, a transformer for each block having its primary connected across said outgoing and return conductor and its secondary across the rails of a block, and signaling devices under the control of the current transmitted through the transformers connected to each block.
- 20 25. A system of automatic signaling for electric railways, comprising a source of electricity, a power circuit fed therefrom, said power circuit including each of the rails of said railway as return paths to the generator, a trackway divided into sections, means for exciting a difference of potential between the respective rails of each section, means for preventing the current due to the difference of potential between the rails of a section flowing to the rails of an adjacent section, and a signaling device in each section controlled as to one movement by the difference of potential between the rails of the section.
- 25 30. A system of automatic signaling for electric railways, comprising a generator, a power circuit of which both rails form a part and a return path to the generator, a trackway divided into sections, means for exciting a difference of potential between the rails of each section, means located at the opposite ends of each section and which
- 30 35. act to oppose the flow of current created by

such difference of potential from one section to the next, and a motor device in each section excited by the difference of potential between the rails of the section, and a signaling device in each section under the control of the motor device.

70 19. A signaling system comprising a source of propulsion current, a source of signaling current, a trackway divided into block sections, means for exciting a difference of potential between the rails of the block sections, reactance bonds connected across the rails at each end of a block section, designed to transmit the propulsion current without saturation or loss of required reactance, and a signaling device in each block section.

75 20. A signaling system comprising a source of propulsion current, a source of signaling current, a trackway divided into block sections, means for exciting a difference of potential between the rails of each section, a reactance bond connected across the rails at each end of a block section, designed to transmit the propulsion current without saturation or loss of required reactance, a transformer in each section, and a relay energized by such transformer and adapted to control a signaling device.

80 21. A signaling system comprising a source of propulsion current, a feeder therefor, a source of signaling current, a feeder therefor, a trackway divided into block sections, means for exciting a difference of potential between the rails of a block section, reactance bonds connected across the rails at each end of a block section, designed to transmit the propulsion current without saturation or loss of required reactance, and a signaling device in each block section.

85 22. In a signaling system the combination of a trackway divided into block sections, reactance bonds designed to transmit the propulsion current without saturation or loss of required reactance connected across the rails at each end of each block section, means for exciting a difference of potential between the rails of each block section, a transformer connected across each block section, and a current translating device energized by the secondary of such transformer.

90 23. In a signaling system the combination of a trackway divided into block sections, reactance bonds designed to transmit the propulsion current without saturation or loss of required reactance connected across the rails at each end of each block section, means for exciting a difference of potential between the rails of each block section and a signaling device in each block section normally actuated by the existing difference of potential.

95 24. In a signaling system the combination of a source of propulsion current, a source of signaling current, a trackway divided

into block sections, means for impressing signaling current upon each block section, means for confining the signaling current to the limits of each block section, and means whereby the rails of the block sections shall serve as separate returns for the propulsion current.

25. A signaling system comprising a source of propulsion current, a source of signaling current, a trackway divided into block sections, means for exciting a difference of potential between the rails of each block section, reactance bonds connected across the rails at each end of a block section designed to transmit the propulsion current without saturation or loss of required reactance, a conductor connecting adjacent bonds, and a signaling device in each block section.

20 26. In a signaling system the combination of a trackway divided into block sections, reactance bonds connected across the rails at each end of each block section designed to transmit the propulsion current without saturation or loss of required reactance, and means for connecting the bonds of adjacent sections together.

25 27. In a signaling system the combination of a trackway divided into block sections, reactance bonds situated at opposite ends of each block section designed to transmit the propulsion current without saturation or loss of required reactance, and means for connecting the bonds of adjacent sections together.

30 28. In a signaling system the combination of a trackway divided into block sections,

reactance bonds situated at opposite ends of each block section designed to transmit the propulsion current without saturation or loss of required reactance, each of said bonds comprising an open magnetic core and a coil thereon connected across the trackway, and means for connecting the coils of adjacent bonds together.

40 29. In a signaling system the combination of a trackway, means for dividing said trackway into block sections and limiting the signaling current to the confines of such block section, said means consisting of insulation introduced between the block sections, and reactance bonds designed to transmit the propulsion current without saturation or loss of required reactance connected across the trackway at each end of a section and a conductor between the bonds.

45 30. In a signaling system the combination of two parallel rails, insulating means for separating said rails into block sections, reactance bonds designed to transmit the propulsion current without saturation or loss of required reactance situated at opposite ends of each block section and each having the opposite terminals of its coils connected to opposite rails, and a conductor for connecting the coils on adjacent bonds together.

50 55 In testimony whereof I have signed my name to this specification in the presence of two subscribed witnesses.
